DESIGN FOR A COMBINATION KEY AND FINGER RING

Emil Gross, Milwaukee, Wis.

Application June 1, 1937, Serial No. 69,642

Term of patent 3½ years

To all whom it may concern:

Be it known that I, Emil Gross, of Milwaukee, in the county of Milwaukee and State of Wisconsin, have invented a new, original, and ornamental Design for a Combination Key and Finger Ring, of which the following is a specification, reference being had to the accompanying drawing, forming part thereof.

In the drawing:

Figure 1 is a front elevational view of the combination key and finger ring showing my new design.

Figure 2 is a side elevation of the same; and
Figure 3 is a plan elevation of the same.

I claim:

The ornamental design for a combination key and finger ring, as shown.

EMIL GROSS.
